UNITED STATES PATENT OFFICE.

ROBERT R. GERRARD, JR., OF ST. JOSEPH, MISSOURI.

BASE-BALL GAME.

1,133,125.

Specification of Letters Patent.

Patented Mar. 23, 1915.

Application filed November 3, 1914. Serial No. 870,112.

To all whom it may concern:

Be it known that I, ROBERT R. GERRARD, Jr., a citizen of the United States, residing at St. Joseph, in the county of Buchanan 5 and State of Missouri, have invented certain new and useful Improvements in Base-Ball Games, of which the following is a specification, reference being had therein to the accompanying drawing.

10 This invention relates to a base ball game and has for its principal object the production of a game board which may be easily set up to represent the usual playing field and which is provided with a number of 15 retaining hooks pegs upon which playing rings may be thrown thereby determining the particular play which is made.

Another object of this invention is the 20 production of a playing board for a base ball game which is provided with a number of hooks for catching the playing rings and which carries at its lower portion a detachably supported bag for receiving the rings which are not caught by the hooks thereby 25 allowing the rings to be easily gathered together when desired.

Still another object of this invention is the production of a playing board for a base ball game which is adapted to be folded to 30 an open position to present an imitation playing field and which is provided with a detachable bottom which may be removed and separated so as to be secured to the rear portions of the game board for forming an 35 easel for supporting the same.

With these and other objects in view this invention consists of certain novel combinations, constructions, and arrangements of parts as will be hereinafter fully described 40 and claimed.

Referring to the accompanying drawings:—Figure 1 is a detailed perspective view of the playing board for a base ball game showing the same in a set-up position and carrying at its lower portion a detachable bag. Fig. 2 is a central vertical section through the playing board showing the same in a set-up position. Fig. 3 is a detailed perspective view of the invention 45 showing the same in a closed position and illustrating the manner in which the sectional detachable bottom is secured in position. Fig. 4 is a central vertical section taken through the playing board showing 50 the same in a closed position. Fig. 5 is a detailed perspective view of the bag. Fig. 6 is a fragmentary side elevation of the lower portion of the playing board showing the detachable bag secured thereto. Fig. 7 is a detailed perspective view of the detachable sectional bottom or base of the board. Fig. 8 is a detailed perspective view of a certain pivot pin used in connection with this device. Fig. 9 is a detailed perspective view of one of the playing rings. 60

Referring to the accompanying drawings by numerals 1 designates the primary section of the playing board and 2 the auxiliary section. These sections are provided with the side strips 3 which extend around their outer portions adjacent their side edges. The plurality of side strips 3 are provided with the hinge members 4 adjacent each end of the sections 1 and 2 for pivotally securing the sections 1 and 2 in engagement 70 with each other thereby allowing the sections to be easily folded to an open or closed position as desired. In order to reinforce the sections 1 and 2 and the side strips 3 there is provided a plurality of metallic bands 5 secured upon the corners of the sections 1 and 2 and the side strips 3, while the outer corners of the side strips and sections are provided with the reinforcing clips 6. It will be seen that by this construction the lower portion of the game board is open when the game board is in a folded or closed position as is clearly shown in Fig. 4. In order to close this open lower portion of the game board there is provided 80 a sectional bottom comprising the strips 7 through which pass the bolts 8 for detachably retaining the same in engagement with each other. These sections which comprise the detachable bottom are adapted to be positioned upon the lower portion of the game board when in a folded position as shown in Figs. 3 and 4. The catches 9 which are carried by the outer strips 7 are swung into engagement with the eyes 10 carried by the 85 sections 1 and 2. In this manner it will be seen that the lower portion of the game board will be closed when the game board is in a folded position. At this time the catch 11 may be thrown into engagement 90 with the eye 12 for retaining the game board in a closed position. There is also provided a handle 13 secured to the upper portion of the game board by means of the eyes 14, and in this manner, the game board may be 95 100 105 110

conveyed from place to place as it will assume a folded position as clearly shown in Fig. 3 resembling somewhat a suit case.

When it is desired to use the board the 5 catches 9 may be removed from engagement with the eyes 10. The catches 11 may then disengage the eyes 12 at which time the sections may be folded to an open position.

The plate 15 will then come into engagement 10 with the plate 16 at which time suitable securing means may be passed therethrough for holding the game board against folding to a closed position. The inner surfaces of the sections 1 and 2 are laid off to represent 15 the usual playing field for a base ball game which carry a number of hooks 17 at spaced intervals in different positions and adjacent which there is formed printed or otherwise placed upon the sections a word or words, as 20 shown at 18, to indicate the particular play which is or is to be made. The circular playing ring, as disclosed in Fig. 9, may then be thrown upon the playing board and

the hook which catches the same will represent the play which has been made. Each 25 play is followed out as in the usual ball game so that the description as to the playing of the game is not deemed necessary. There is also provided alined eyes 12' carried by the side strips 3 of the auxiliary 30 section 2 which are positioned in alignment with the eyes 12. A bolt member 20 having a head 21 is adapted to be positioned at each end of the auxiliary section 2 and 35 to be carried by the alined eyes 12 and 12'. This bolt member 20 is adapted to pass through the sleeve portion 22 formed in each 40 end of the bag 23 which is preferably rectangular in shape so as to extend across the lower portion of the playing board when the same is in a set-up position as shown in Fig. 1. This bolt member 20 will retain 45 the bag in an open position so that when a ring is not caught by one of the hooks 17 it will roll down and fall into the bag 23.

After the supply of rings has been exhausted the rings may be easily gathered from the bag 23 for the continued playing of the game.

50 In order to retain the playing board in a set-up position as shown in Fig. 2, the sectional bottom may be separated by the removal of the bolts 8. The strips 7 carry the hinged sections 24 which are adapted to engage the hinged sections 25 secured to the 55 side portions of the primary section 1. A pin 26 may then be passed through the hinged sections for detachably securing the strips 7 in engagement with the primary section 1. In this manner, it will be seen 60 that the strips 7 will form an easel for supporting the game board in a set-up position so as to allow the game board to slightly lean in one direction for allowing the playing rings to be more easily caught by the

hooks 17 than would be the case if the game board assumed a vertical position or rested evenly upon a supporting surface.

From the foregoing description it will be seen that a simple and efficient game board 70 has been produced which is provided with a simple and efficient means for playing a base ball game by means of a plurality of playing rings and retaining hooks and which carries at its lower portion a bag for catching 75 the loose rings thereby preventing the rings from being lost and allowing the same to be more easily collected. Furthermore, this game board is so formed as to be easily folded as will be seen by referring to the above 80 description, at which time a sectional detachable bottom will close the lower portion of the board but it is to be noted, however, that this bottom may be easily disassembled and secured to the rear portions of the primary 85 section of the board for forming an easel for supporting the board in a set-up position when the same is in use.

What I claim is:

1. A playing board for a base ball game 90 comprising a pair of hinged sections, said sections provided with side strips, retaining hooks carried by said sections, said hooks being adapted to receive playing rings, and a detachable bag carried at the 95 lower portion of said playing board for receiving the rings which are not caught by said hooks.

2. In a device of the class described the combination with a pair of hinged sections, 100 a plurality of hooks carried by said sections, said hooks being adapted to catch playing rings, one of said sections provided with alined eyes upon its outer portions, detachable bolts carried by said eyes and a bag 105 detachably supported upon said bolts, said bag adapted to be supported adjacent the lower portion of said playing board, whereby rings which are not caught by said hooks may fall into said bag for allowing the rings 110 to be easily caught and collected.

3. In a device of the class described the combination with a pair of hinged sections, 115 said sections provided with an imitation playing field, hooks carried by said sections, said hooks being adapted to receive playing rings, one of said sections provided with alined eyes adjacent its lower outer portions, bolts detachably supported by said eyes, said bolts provided with retaining heads, a bag 120 having sleeve portions mounted upon said bolts whereby said bag will be held adjacent the lower portion of said playing board, said bag having a rectangular construction whereby rings which are not caught by said 125 hooks may fall into said bag thereby allowing the rings to be easily caught and collected.

4. In a device of the class described the combination with a pair of hinged sections, 130

said sections being adapted to be folded to a closed position to form a box-like construction, a detachable bottom secured to said sections for closing the lower portions 5 thereof, said bottom being adapted to be detached and secured to the outer portions of one of said sections for forming an easel for supporting the device in a set-up position.

5. In a device of the class described the 10 combination with a pair of hinged sections, said sections being adapted to be folded to a closed position, a detachable bottom for closing the lower portions of said sections, said detachable bottom comprising a plurality of strips detachably secured together, 15 said strips being adapted to be detached

from said sections and from each other, hinge members carried by said strips and by one of said sections, said strips being adapted to be positioned so as to allow the hinge members thereof to engage the hinge member of one of said sections, whereby said detachable bottom will form an easel for supporting said sections in a set-up position. 20

In testimony whereof I hereunto affix my signature in presence of two witnesses.
